(57) **CLAIM**

The ornamental design for a grow panel light, as shown and described.

DESCRIPTION

- FIG. 1 is a top perspective view of a grow panel light according to the present invention;
FIG. 2 is a bottom perspective view thereof;
FIG. 3 is a front elevation view thereof, the rear elevation view being mirror image thereof;
FIG. 4 is a left side view thereof, the right side view being mirror image thereof;
FIG. 5 is a top side view thereof;
FIG. 6 is a bottom side view thereof;
FIG. 7 is an enlarged top perspective view of a feature thereof shown in FIG. 1;
FIG. 8 is an enlarged top perspective view of a feature thereof shown in FIG. 1;
FIG. 9 is an enlarged bottom perspective view of a feature thereof shown in FIG. 2;
FIG. 10 is an enlarged bottom perspective view of a feature thereof shown in FIG. 2;
FIG. 11 is an enlarged front elevation view of a feature thereof shown in FIG. 3;
FIG. 12 is an enlarged front elevation view of a feature thereof shown in FIG. 3;
FIG. 13 is an enlarged left side view of a feature thereof shown in FIG. 4;
FIG. 14 is an enlarged top side view of a feature thereof shown in FIG. 5;
FIG. 15 is an enlarged bottom side view of a feature thereof shown in FIG. 6;
FIG. 16 is a fragmentary cross-sectional view taken along lines 16-16 of FIG. 5;
FIG. 17 is a fragmentary cross-sectional view taken along lines 17-17 of FIG. 5;
FIG. 18 is a fragmentary cross-sectional view taken along lines 18-18 of FIG. 5;
FIG. 19 is a fragmentary cross-sectional view taken along lines 19-19 of FIG. 5;
FIG. 20 is an enlarged fragmentary cross-sectional view of a feature thereof shown in FIG. 16;
FIG. 21 is an enlarged fragmentary cross-sectional view of a feature thereof shown in FIG. 16;
FIG. 22 is an enlarged fragmentary cross-sectional view of a feature thereof shown in FIG. 17;

(Continued)

FIG. 23 is an enlarged fragmentary cross-sectional view of a feature thereof shown in FIG. 18; and,

FIG. 24 is an enlarged fragmentary cross-sectional view of a feature thereof shown in FIG. 19.

The broken lines showing in the drawings are for the purpose of illustrating portions of the grow panel light and form no part of the claimed design.
